UNITED STATES PATENT OFFICE.

WILLIS A. TAYLOR, OF PRESQUE ISLE, MAINE.

SHAVER'S CABINET.

1,226,723.

Specification of Letters Patent. Patented May 22, 1917.

Application filed May 22, 1916. Serial No. 99,204.

To all whom it may concern:

Be it known that I, WILLIS A. TAYLOR, a subject of the King of Great Britain, residing at Presque Isle, in the State of Maine, 5 United States of America, have invented certain new and useful Improvements in Shavers' Cabinets; and I do hereby declare that the following is a full, clear, and exact description of the invention, such as will 10 enable others skilled in the art to which it appertains to make and use the same.

The present invention relates to a shaver's cabinet and more particularly to a portable and compact cabinet for carrying a shaver's 15 outfit and an object of the invention is to provide a cabinet for the individual use which will be simple and compact in arrangement, durable, strong and efficient in use and one which will be comparatively in- 20 expensive in the cost of manufacture thereby rendering the same commercially desirable.

With the above and other objects in view which will hereinafter appear as the de- 25 scription continues, the invention consists of the novel features of construction and the formation of parts as will be hereinafter more fully described and particularly pointed out in the appended claims.

30 In the accompanying drawings is shown the simple and preferred form of the invention it being, however, understood that no limitation is necessarily made to the precise structural details herein exhibited but 35 the right is hereby reserved to any changes or alterations that may be had and come within the scope of the invention without departing from the spirit thereof or sacrificing the efficiency of the same.

40 In the drawings:

Figure 1 is a side elevation of the cabinet embodying the present invention;

Fig. 2 is a transverse section of the same on the line 2—2 of Fig. 1;

45 Fig. 3 is a plan view of the cover when removed;

Fig. 4 is a detail section through the handle;

Fig. 5 is a plan view of the cabinet show- 50 ing an ordinary strap secured thereto;

Fig. 6 is a plan view of the cabinet with the cover thereof open and a portion of the latter being broken away;

Fig. 7 is a detail side elevation of the 55 cover shown in Fig. 5 when removed; and

Fig. 8 is a detail plan view of one of the straps shown in Fig. 1.

Reference now being had to the accompanying drawings wherein like and corresponding parts are designated by similar reference characters throughout the several views—

The numeral 1 indicates a cabinet which is of rectangular configuration and formed of a single block of wood having one face 65 thereof mortised out and divided into compartments in which are adapted to be placed the various accessories used by the operator.

Arranged within one end of the recess formed within the cabinet 1 is a block 2 hav- 70 ing a recess 3 therein in which may be placed shaving soap. The remaining portion of the recess within the cabinet is divided into compartments by means of the partitions 4 so as to provide a compartment 5 in which may 75 be placed a razor; a compartment 6 in which may be placed a shaving brush, a compart- 80 ment 7 in which may be placed a small can of talcum powder; a compartment 8 in which may be placed a styptic pencil and in 85 the compartment 9 a small hone may be placed.

Hingedly connected as at 10 to one end of the cabinet is a cover 11 adapted to close the compartments within the cabinet and 85 this cover 11 is provided with a lock 12 whereby it may be locked in place to prevent unauthorized persons from gaining access within the interior of the cabinet. A looking-glass 13 is arranged upon the inner 90 face of the cover 11 and a chain or other flexible member 14 connects one end of the cover with the cabinet 1 so as to limit the outward movement of the cover or hold the cover in any desired raised position so that 95 the looking-glass when the cover is open will be presented for use. Extending from one end of the cabinet 1 is a handle 15 hav- 100 ing a recess therein in which is adapted to be placed a glass bottle 16 for holding toilet or other liquid used in shaving. Detach- 105 ably connected to the handle 15 is a cover 17 which holds the glass bottle 16 in place and conceals the same from view.

Secured to each side of the cabinet 1 are 105 the honing stones 18 and in Figs. 5 and 7 the razor straps 19 are rigidly secured as at 20 to the upper face of the cover 11 and to the lower face of the cabinet 1. The strap 19 arranged upon the upper face of the cover 110

may be of leather and the strap secured to the bottom of the cabinet may be of canvas or any other suitable razor strapping material.

Secured to one end of the cabinet 1 as shown in Fig. 1 is a pair of staples 21 and 22. Pivotaly connected to the staple 21 is a strap of leather 23 having connected or interwoven in any desired manner an elastic strip 24 to which are connected the members 25 of the spring catches. Secured to the staple 22 is a strap of canvas 26 also having connected to its free end an elastic band 27 provided with the catches 28. From this it is apparent that the straps 23 and 26 may be released at one end from the cabinet and may be used for sharpening the razor in the usual manner but when they are out of use the catches 25 and 28 may be used for fastening the free ends of the straps to the cabinet 1 and when so connected the strap 23 will provide a locking means for retaining the cover 11 in position.

The straps 19 as shown in Figs. 5 and 7 are rigidly connected at their opposite ends as at 20 to the outer face of the cover 11 but the medial portion of this strap is adapted to bulge out as the strap is of greater length than the distance between the points of its connection to the cover, so that it will give or be allowed to play when the razor is being sharpened as is essential.

As the straps 19 may be applied to a cabinet having the straps 23 also secured thereto, it is evident that by having these two sets of straps the straps 23 may be unfastened so

that access may be gained into the cabinet and at the same time the straps 19 will be presented for use without the necessity of again fastening the straps 23.

Having thus fully described my invention, what I claim as new and desire to secure by Letters Patent is:

1. A device of the character described comprising a cabinet having a rectangular configuration, and compartments arranged therein, a cover for closing said compartments, staples carried by one end of said cabinet, a pair of straps each having one end connected to said staples, an elastic webbing formed with the opposite ends of said straps, means for detachably connecting said elastic portions of said straps to the cabinet and one of said straps adapted to hold said cover in closed position substantially as and for the purpose specified.

2. A shaver's cabinet comprising a receptacle having a plurality of compartments formed therein, a cover for said receptacle, straps pivotally connected at one end to said receptacle, means for detachably connecting the opposite ends of said straps to the receptacle and means whereby said cover will be held in closed position by one of said straps for the purpose set forth.

In witness whereof I have hereunto set my hand.

WILLIS A. TAYLOR.

Witnesses:

CHARLIE F. DAGGETT,
LAUREL M. WALLACE.
